UNITED STATES PATENT OFFICE.

EDWIN D. STALFORT, OF BALTIMORE, MARYLAND.

CONCAVE ROLLED SUCTION-CUP HEEL.

1,292,120.

Specification of Letters Patent. Patented Jan. 21, 1919.

Application filed November 3, 1917. Serial No. 200,134.

To all whom it may concern:

Be it known that I, EDWIN D. STALFORT, a citizen of the United States, residing at Baltimore, in the State of Maryland, have 5 invented new and useful Improvements in Concave Rolled Suction-Cup Heels, of which the following is a specification.

This invention relates to heel lifts, and comprehends certain new and useful 10 improvements in heel lifts of the type illustrated in Reissue Patent 14,049.

Heel lifts such as that disclosed in the above mentioned patent, and others of an analogous character are formed with a concave upper surface with a view of creating a 15 partial vacuum when the lift is operatively associated with the heel of the shoe. However by reason of the cross sectional configuration of the lift above referred to, which 20 is of concavo-convex form on every line of cross section, the lift is deprived of a straight edge which is an absolute necessity for the purpose of solidifying the resilient lift to the leather or wooden heel of the shoe, to 25 prevent riding of the resilient lift beyond the edges of the heel as well as to obviate loosening of the nails or other fastening elements employed in securing the lift to the heel of the shoe. It has been found by 30 experience, that when a lift of this peculiar contour is pressed or flattened against the heel of the shoe, and subsequently secured by nails or other fastening elements, the lift has a tendency to ride or move relative to the 35 heel of the shoe, by reason of the absence of a straight edge, which as above stated is so essential in the elimination of this objection. Again, when a lift of this contour has been 40 associated with the heel of the shoe, the lift by reason of the inherent quality of the rubber has a tendency to resume its normal position, namely concavo-convex in cross section, and this tendency of the lift obviously results in spacing both the side and breast 45 edges of the lift from the heel of the shoe, as well as loosening the fastening elements. This is particularly true after the heel has become partly worn.

The object of the present invention is the 50 provision of a concaved resilient lift curved in longitudinal and transverse section, whereby a suction effect will be produced when the lift is applied to a shoe heel, and having the upper edge of its forward end or breast lying in a straight horizontal plane

whereby said edge will always lie against the heel without the possibility of downward buckling away from the forward edge of the heel resulting from any loosening of the 55 nails employed to secure the lift in place; this construction reducing to a minimum the possibility of the lift slipping or riding upon the heel.

Another object of importance resides in providing a suction cup disposed within the 60 concavity of the lift, with the upper edge of the cup disposed above the lowermost area of the lift to assure spreading of the free edge of the cup against the heel proper, during the association of the lift with the heel. 70

The nature and advantages of the invention will be better understood from the following detail description when read in connection with the accompanying drawing, the invention residing in the construction, 75 combination and arrangement of parts as claimed.

In the drawing forming part of this specification like numerals of reference indicate similar parts in the several views and where- 80 in:

Figure 1 is a fragmentary side elevation of a shoe showing the resilient heel lift arranged against the heel proper of the shoe, prior to securing the lift thereto. 85

Fig. 2 is a similar view showing the heel lift secured to the heel proper.

Fig. 3 is a perspective view of the heel lift.

Fig. 4 is a sectional view taken on line 90 4-4 of Fig. 3 looking from the breast of the lift.

Fig. 5 is a similar cross sectional view looking from the back of the lift.

Referring more particularly to the drawing, the numeral 10 designates the heel of a shoe to which my lift 11 is applied. The lift is formed of rubber and is concaved in its upper face, being curved in both longitudinal and transverse section, as shown. An 95 important feature is the fact that the upper edge 13 of the front portion or breast lies in a straight, horizontal plane and will bear throughout its length, against the shoe heel even before the lift is secured in place. The 100 lift, after being placed against the heel, is secured by means of nails or other similar fastening members 12 countersunk within openings 14 and passing through metallic washers 16. After being thus secured the 105 110

central or depressed portion of the lift will be held in close engagement with the heel and will help hold the lift in place by suction.

Now, referring to Fig. 1 of the drawing, it will be noted that the lift constructed in accordance with my invention is merely arranged against the heel 10 of the shoe, and is not in any way secured thereto. However by reason of the contour of the lift the straight edge 13 throughout its entire length contacts the heel proper while the rear edge of the lift is also disposed in contacting engagement with the heel. When arranged in this manner the fastening elements 12 are driven through the openings 14 into the heel 10, and as the central portion of the lift is thus drawn into close association with the heel 10, a suction will be produced, helping to hold the lift in place. As the edge 13 is straight, there will be no tendency toward downward buckling at the center of the front of the lift and the danger of catching the heel and tearing it loose is greatly reduced. It will be noted that this construction greatly reduces the danger of the lift slipping or riding upon the heel as the front edge gives a good bearing and as rubber itself tends to grip instead of slipping. Projecting from the centrally depressed area 17 is a suction cup 18, which is of sufficient dimensions to extend above the lowermost portion of the face of the heel from which it projects, so that when the lift is secured to the heel 10 the free edge of the cup will be properly spread against the heel 10 to create a suction with the desired effect of maintaining the lift properly positioned upon the heel. It is a well known fact that the bottom of the heel 10 in most shoes, and in fact in all shoes does not present a perfectly smooth surface, and consequently by reason of the particular size and arrangement of the cup 18, the latter will accommodate itself to the irregularities of the heel 10 which may exist. This of course would

not be true if the cup 18 terminated flush with the lowermost surface of the lift. Surrounding the cup 18 is a groove 19 and when the lift is secured to the heel 10 the free edge 50 of the cup 18 when spread, overlies the groove 19 closing the latter in the manner clearly illustrated in Fig. 2. The lift is thus provided with a plurality of suction areas as shown, which all coöperate or assist in 55 maintaining the lift effectively secured to the heel proper.

While it is believed that from the foregoing description the nature and advantages of the invention will be readily apparent, I desire to have it understood that what is herein shown and described is merely illustrative of the preferred embodiment, to which I do not limit myself, and that such changes in the construction, size and configuration may be resorted to when desired as fall within the scope of what is claimed.

What is claimed is:—

1. A cushion shoe lift comprising a longitudinally curved body having its upper surface concaved in longitudinal and transverse section and having the upper edge of its breast lying in a horizontal plane, the upper side edges of the body being normally curved and lying below the plane passing 75 through the edge at the breast and the most rearward point of the upper edge of the body.

2. A cushion shoe lift comprising a body concaved in its upper surface, and a suction 80 cup formed centrally of said concaved portion and extending beyond the tops of the sides of the lift.

3. A cushion shoe lift comprising a resilient body concaved in its upper face, and 85 an upstanding projection formed integrally upon the center portion of the concavity, said projection being conically recessed to form a cup having its edges extending above the edges of the top.

In testimony whereof I affix my signature.
EDWIN D. STALFORT.
